PUMP LINER

Walter T. Janney and Maximillian H. Sorensen,
Philadelphia, Pa., assignors to Janney Cylinder
Company, Philadelphia, Pa., a corporation of
Pennsylvania

Application July 27, 1937, Serial No. 155,936

4 Claims. (Cl. 309—3)

This invention relates to pump liners, and particularly to a composite pump liner for slush pumps and the like used in the oil industry.

It is well known that slush or sludge pumps are designed to circulate a fluid mud which is possessed of a high abrasive factor normally effective to preclude any but a short life for the pump. For this reason it has become necessary to provide separable and renewable liners for such pumps that can be removed and replaced as desired, although obviously such renewing is at considerable cost. Unfortunately the abrasive factor is accompanied by others requiring entirely different characteristics in the liner, namely, great strength to resist the shocks of pumping. Obviously the abrasion resisting and strength characteristics are two antagonistic factors incapable of satisfactory solution by the same metal.

It is among the objects of this invention to provide a liner possessed of great strength as well as high resistance to abrasion; to provide a composite liner with means preventing undesired separation of the elements thereof; to provide a steel lining shell with a welded steel ring engaging an end of a brittle abrasion-resisting inner member to prevent relative axial movement of the parts in one direction; and many other objects and advantages as will become more apparent as the description proceeds.

The pump, not shown, of any conventional design is arranged to receive the composite insert comprising an outer jacket of high tensile strength and high elongation, with an inner sleeve of high wear resistance having substantially no elongation and only moderate tensile strength, with means anchoring the parts against axial relative movement.

In the accompanying drawing:

Fig. 1 represents a vertical longitudinal section through a compound liner according to this invention, and

Fig. 2 represents a fragmentary enlarged longitudinal vertical section through the end of the assembly disclosing the anchoring portions.

The compound liner has an outer shell 10 preferably of high physical strength, but of low abrasion resistance, and of high elongation, and illustratively, made of steel. It may simply be of soft steel unsuitable for abrasion resistance. One end may be threaded as at 11 to receive the threaded flange 12 by which the compound liner is secured in the pump, as will be readily understood. The end 13 opposite to the threaded end 55 is provided with the reduced inner periphery or

counter-bore 14 terminating internally in the shoulder 15 and externally in the inclined or chamfered surface 20.

The inner sleeve 16 is preferably of heat treated cast iron which is hard and possessed of high abrasion resistance but low physical strength and has an enlarged flange like portion, head or bead 17 of a size to fit in the counterbore 14, and has a shoulder 18. The inner hard, and generally brittle, sleeve 16 is slid axially into the outer sleeve in substantially intimate physical contact therewith throughout their common length, with the bead 17 in the axial recess 14, with the shoulder 18 engaging shoulder 15 of the outer housing or strengthening sleeve 10. It will be apparent that the interlocking shoulder engagement securely anchors the inner and outer sleeves together against relative axial movement in one direction only, and the parts can be axially disengaged in the other direction unless otherwise prevented.

To anchor the parts against such axial disengagement the counterbore 14 is prolonged beyond the end of the bead 17 and, preferably, merges into the inclined chamfer 20 in the end 25 13 of the strengthening sleeve. A short relatively soft steel ring 21 of such diameter as to have a sliding fit in the steel outer cylinder abuts the end of the bead or enlarged head 17 of the hardened abrasion resisting inner member 16, and has a cooperatively chamfered surface 22 meeting inclined surface 20 in an oblique angle. The ring is of such material as conduces to welding of the ring to the outer shell, and the welding 24 rigidly anchors the ring in the shell. 30 35

Obviously the inner member is thus anchored at a single end to the outer shell so that elongation of the outer shell relative to the inner sleeve develops no shearing strains, no tensile stresses are developed, and the effective inner and outer diameters of the pump entering end of the composite sleeve or liner are the same as the main body thereof. This latter is an important factor, as the liner must be capable of 40 axial insertion in the pump (not shown) and variations in diameter would interfere with such sliding insertion.

It is pointed out that the anchoring association is secured without subjecting the hardened inner sleeve itself to welding or other stressing action which might crack same, and being clamped at one point or end can slide with the anchor point as the outer shell elongates or shrinks according to conditions in operation. 50 55

We claim:

1. A compound liner comprising a shell of material of high tensile strength and elongation having a counterbore, a sleeve shorter than said shell and of high resistance to abrasion having a shouldered head of a diameter to seat in the counterbore, said sleeve telescoping with said shell to bring said shoulder against the end of the counterbore and forming an annular space 10 at the outer end of said counterbore, a ring in said annular space in substantial abutment with the end of said sleeve, said ring having the same internal and external diameter as the shouldered head and of a length such as substantially to fill 15 the space to the end of the shell, and means anchoring the ring and shell together to prevent relative axial movement in the other direction.
2. A compound liner comprising a strong steel shell of low abrasion resistance, and having a counterbore, a hardened cast iron sleeve having an enlarged end disposed in the shell with the enlarged end in the counterbore and leaving a space from the end of the shell, a steel ring in the counterbore abutting the sleeve end and of 25 a length substantially equal to said space and having the same internal diameter as the sleeve, said ring and shell being welded together throughout the peripheral extent of the ring to absorb stresses on said ring evenly.
3. A compound liner comprising a strong steel shell of low abrasion resistance having a counterbore with its end internally chamfered in communication with the counterbore, a hardened

cast iron sleeve having an enlarged end in the counterbore, a steel ring in the counterbore abutting the sleeve end and of the same thickness as the enlarged end and having an internal diameter the same as that of the sleeve to form an 5 effective extension thereof and being axially of a length such as to substantially fill the space from said sleeve end to the end of the counterbore, said ring having an externally chamfered end forming with the chamfer of the steel shell 10 an annular gutter, and welding material in said gutter to weld the ring and shell together throughout their adjacent end peripheries.

4. A compound liner comprising a tubular shell of high tensile strength and elongation 15 formed with a counterbore at one end, said shell having a length substantially equal to a selected piston cylinder, a cast iron sleeve shorter than said shell and having an annular flange at one end of a diameter to fit within said counterbore 20 and of a thickness to leave an external annular space in said counterbore when said sleeve is telescoped with said shell and said flange seated on the end of said counterbore, said construction preventing relative expansion movement between said shell and sleeve at the counterbore end of the assembled parts, a retaining ring in said annular space having an internal diameter 25 to permit free passage of a piston, and means to anchor said ring and shell together. 30
